(57) **CLAIM**

The ornamental design for a therapy device base stand, as shown and described.

DESCRIPTION

FIG. 1 illustrates a front perspective view of a therapy device base stand;

FIG. 2 illustrates a bottom perspective view of the therapy device base stand thereof;

FIG. 3 illustrates a front view of the therapy device base stand thereof;

FIG. 4 illustrates a back view of the therapy device base stand thereof;

FIG. 5 illustrates a left side view of the therapy device base stand thereof;

FIG. 6 illustrates a right side view of the therapy device base stand thereof;

FIG. 7 illustrates a top view of the therapy device base stand thereof;

FIG. 8 illustrates a bottom view of the therapy device base stand thereof;

FIG. 9 illustrates a front perspective view in folded position of the therapy device base stand thereof;

FIG. 10 illustrates a top view in folded position of the therapy device base stand thereof;

FIG. 11 illustrates a cross sectional view along line 11-11 of FIG. 1; and,

FIG. 12 illustrates a cross sectional view along line 12-12 of FIG. 10.

The broken lines in the drawings depict portions of the therapy device base stand that form no part of the claimed design.

1 Claim, 11 Drawing Sheets
